UNITED STATES PATENT OFFICE.

JOSEPH BAERAJA-FRAUENFELDER; OF BRIDGEPORT, CONNECTICUT, ASSIGNOR TO THE LAKE TORPEDO BOAT COMPANY OF MAINE, OF BRIDGEPORT, CONNECTICUT, A CORPORATION OF MAINE.

ANCHOR-CABLE-CUTTING APPARATUS FOR SUBMARINE BOATS.

1,158,160.

Specification of Letters Patent.

Patented Oct. 26, 1915.

Application filed March 8, 1915. Serial No. 12,832.

To all whom it may concern:

Be it known that I, JOSEPH BAERAJA-FRAUENFELDER, a citizen of the United States, residing at Bridgeport, in the county of Fairfield and State of Connecticut, have invented certain new and useful Improvements in Anchor-Cable-Cutting Apparatus for Submarine Boats, of which the following is a Specification.

10 The invention relates to an improved apparatus for cutting the supporting cables of anchors carried by submarine boats so as to release the anchors in the event of accident to the boat, or in the event of the anchors becoming so tightly locked in the water-bed that they cannot be lifted by the hoisting apparatus.

15 The invention has for its object to provide a simple and efficient arrangement for 20 protecting the cutting blades from the water when the boat is submerged, and thus prevent them and their operating parts from being impaired through rust.

25 The invention consists in providing a casting or housing for the cutting blades, and in the peculiar and novel provision of a sleeve of lead or other soft metal providing a passage through the casing through which the anchor-cable operates, the said cutting 30 blades being so arranged to provide a shearing cut upon the said sleeve and the cable whereby the cable may be cut with the exertion of but little power.

35 The invention further consists in certain details of construction and novel arrangements of parts as will be hereinafter described and then claimed.

40 In the drawings illustrating the invention, in the several figures of which like parts are similarly designated, Figure 1 is a diagrammatic vertical longitudinal section of the forward end of a submarine or submersible boat illustrating the application of my invention. Fig. 2 is a horizontal section 45 drawn on a larger scale on the line *a—a* of Fig. 1. Fig. 3 is a sectional view on the line *b—b* of Fig. 2, part of the sheave over which the cable operates being broken away.

1 designates the forward end of a submarine or submersible boat having an anchor well 2 arranged therein; and 3 designates the superstructure of the boat into which the upper end of the well 2 opens, these parts and general arrangement there-

of being of the design common in boats of the Lake type.

Upon the top of the hull plating and having an opening which registers with the upper end of the well 2, is a casting 4 upon which is mounted and secured in suitable manner, the base 5 of the lower half of a sectional casing or housing 6, each section having an opening 8 in which is held a sleeve 9, preferably of lead, but which may be of any suitable soft metal. The said sleeve passes through the casing and has its ends bent or flanged outwardly as at 9' and designed to rest upon shoulders 10 surrounding the openings 8. The sleeve 9 is held in place by nuts 11 which are threaded into the outer ends 12 of the openings 8, the said nuts being provided with central openings and also with annular flanges 13 which are designed to fit into the respective ends of the sleeve 9, and also with knife edges 14 which are designed to engage and cut into the flanges 9' of the sleeve 9 so as to provide water-tight joints and thus prevent ingress of water to the casing or housing 6 when the boat is submerged.

Journalized in bearings 6' formed in the upper and lower sections of the casing 6, is an idle shaft 15' having a segmental worm gear 15 loosely journaled thereon, the teeth of which are meshed by a worm 16, carried by a shaft 16' journaled in the casing 6, and having one end extended through the casing and provided with a bevel gear 17 which is meshed by a bevel pinion 18 carried at the upper end of a vertical shaft 19 journaled in a bearing 20 secured to the hull, and in a stuffing box formed in said bearing, the inner end of the shaft being extended into the main hull and provided with a hand wheel 21 as shown in Fig. 1.

The segmental worm gear 15 is provided with an extension 22 having a recess 22' in which is securely held a cutting blade 23 having a curved cutting edge as shown, and secured to a boss 24 formed integral with the lower section of the casing or housing, is a stationary cutting blade 25 having a semi-circular recess formed with a cutting edge 26 which is positioned so that it partly surrounds and lies immediately adjacent to the sleeve 9 as shown most clearly in Fig. 2.

27 designates the anchor and 28 the cable therefor, the said cable being extended up-

wardly through the well, through the nuts 11, and through the sleeve 9, and passes over a guide sheave 29 suitably journaled within the superstructure 3 of the boat, the cable 5 having its inner end wound upon a drum (not shown) which may be of any suitable design, but preferably of the design shown in Letters Patent No. 716,059 granted to Simon Lake, December 16, 1902.

10. In operation, when the hand wheel 21 is rotated, motion will be imparted to the segmental gear which will cause the cutting blade 23 to be moved into contact with, and to impart a shearing cut to the sleeve 9, and 15 to the cables 28, it, of course, being understood, that the said sleeve and the cable will be first pushed over by the blade 23 into engagement with the stationary co-acting cutting blade 25 and then upon a continued 20 movement of the blade 23, the sleeve and cable will be severed.

From the foregoing, it will be seen that I provided an exceedingly simple and efficient apparatus whereby the cutting blades are 25 kept free from rust and hence in an efficient condition at all times.

In practice the casing or housing will be filled with vaseline, Albany grease, or other semi-fluid lubricant the same being supplied 30 to the said casing or housing through an opening formed in the upper section thereof which is closed by a threaded plug 40 so as to prevent ingress of water to the casing or housing when the boat is submerged. It will be further understood that by completely filling 35 the casing or housing with a suitable lubricating material, that when the boat is submerged to any depth the external pressure of the water upon the wall of the sleeve 40 will be counterbalanced and hence have no affect upon the sleeve, so that damage to the sleeve will be avoided. It will also be understood that by providing the clamping nuts of the sleeve with the tubular extensions 45 extending into the sleeve, that the latter is protected from wear when the anchor-cable passes through the sleeve, as when raising or lowering the anchor weight.

What I claim is:

50. 1. In an anchor-cable cutting apparatus for vessels, a pair of co-acting anchor-cable cutting blades arranged exteriorly of the vessel, means operable from within the interior of the vessel for actuating one of said cutting blades, and a protecting casing or housing for said cutting blades.

2. In combination with a submarine boat, provided with an anchor weight and an anchor-cable connected to said weight, of apparatus arranged exteriorly of the hull of the boat for cutting said cable, and a protecting casing or housing for said cutting apparatus.

3. In combination with a submarine boat, 55 provided with a superstructure and having

an anchor well in the main hull thereof; an anchor weight normally housed within said well, and an anchor-cable connected to said weight and extending from said superstructure, of an apparatus for cutting said cable, 70 said apparatus comprising a fixed and a movable cutting blade, means operable from within the boat for actuating said movable blade, and a protecting casing or housing for said cutting blades.

4. In combination with a submarine boat, provided with a superstructure and having an anchor well in the main hull thereof; an anchor weight normally housed within said well, and an anchor-cable connected to said weight and extending from said superstructure, of an apparatus for cutting said cable, said apparatus comprising a fixed and a movable cutting blade, means operable from within the boat for actuating said movable blade, and a protecting casing or housing for said cutting blades, said cable passing through said casing or housing.

5. In combination with a submarine boat, provided with a superstructure and having 80 an anchor well in the main hull thereof; an anchor weight normally housed within said well, and an anchor-cable connected to said weight and extending from said superstructure, of an apparatus arranged within the 90 superstructure for cutting said cable, said apparatus comprising a fixed and a movable cutting blade, means operable from within the boat for actuating said movable cutting blade, a protecting casing or housing for 100 said cutting blades having an opening through which said cable passes, and a sleeve of soft metal surrounding said cable and connected water-tight to said casing or housing.

6. In combination with a submarine boat, provided with a superstructure and having an anchor well in the main hull thereof; an anchor weight normally housed within said well, and an anchor-cable connected to said weight and extending from the superstructure, of an apparatus arranged within the superstructure for cutting said cable, for the purpose specified, said apparatus comprising a fixed and movable cutting blade, 115 means operable from within the boat for actuating said movable cutting blade, a protecting casing or housing for said cutting blades having an opening through which the said cable passes, a sleeve of soft material 120 arranged within said opening and surrounding said cable, and clamping nuts for connecting the ends of said sleeve to said casing or housing air- and water-tight, said nuts serving to protect the said sleeve when the 125 said cable passes therethrough.

7. In combination with a submarine boat, provided with a superstructure and having an anchor well in the main hull thereof; an anchor weight normally housed within said 130

well, and an anchor-cable connected to said weight and extending from said superstructure, of an apparatus arranged within the superstructure for cutting said cable, said 5 apparatus comprising a fixed and a movable cutting blade, means operable from within the boat for actuating said movable cutting blade, a protecting casing or housing for said cutting blades having an opening through which said cable passes, and a sleeve of soft metal surrounding said cable and connected 10 to said casing or housing, said cutting blade being so arranged to produce a shearing cut upon said sleeve and said cable.

10 which said cable operates, a sleeve of soft material arranged within the opening and surrounding said cable, said sleeve being connected air- and water-tight to said casing or housing, said casing or housing being de- 15 signed to be filled with lubricant, for the purposes specified.

8. In combination with a submarine boat, provided with a superstructure and having an anchor well in the main hull thereof, an 20 anchor-weight normally housed within said well, and an anchor-cable connected to said

weight and extending from said superstructure, of an apparatus for cutting said cable, comprising a fixed and a movable cutting blade, means operable from within the boat 25 for actuating said movable cutting blade, a protecting casing or housing for said cutting blades having an opening through which said cable passes, and a sleeve of soft metal surrounding said cable and connected 30 to said casing or housing, said cutting blade being so arranged to produce a shearing cut upon said sleeve and said cable.

In testimony whereof I have hereunto set 35 my hand this 12th day of February, A. D. 1915.

JOSEPH BARRAJA-FRAUNFELDER.
